Primary Examiner — Mojtaba Tehrani(74) *Attorney, Agent, or Firm* — NKL Law; Allen Xue(57) **CLAIM**

The ornamental design for a digital spotting scope as shown and described.

DESCRIPTION

FIG. 1 is a top, front, left side perspective view of a digital spotting scope, showing our new design;

FIG. 2 is a top, rear, left side perspective view thereof;

FIG. 3 is a top, rear, right side perspective view thereof;

FIG. 4 is a top, front, right side perspective view thereof;

FIG. 5 is a bottom, rear, left side perspective view thereof;

FIG. 6 is a front elevation view thereof;

FIG. 7 is a rear elevation view thereof;

FIG. 8 is a left side elevation view thereof;

FIG. 9 is a right side elevation view thereof;

FIG. 10 is a top plan view thereof; and,

FIG. 11 is a bottom plan view thereof.

The broken lines in the drawings show portions of the digital spotting scope that form no part of the claimed design.
